UNITED STATES PATENT OFFICE.

WILLIAM KABEL, OF MILWAUKEE, WISCONSIN.

AUTOMATIC REWIND MECHANISM FOR MOTORS.

1,425,863.

Specification of Letters Patent. Patented Aug. 15, 1922.

Application filed February 10, 1921. Serial No. 443,937.

To all whom it may concern:

Be it known that I, WILLIAM KABEL, a citizen of the United States, and resident of Milwaukee, in the county of Milwaukee and State of Wisconsin, have invented certain new and useful Improvements in Automatic Rewind Mechanism for Motors; and I do hereby declare that the following is a full, clear, and exact description thereof.

10 My invention refers to means for automatically rewinding the spring motors or the like for musical instruments, clocks, or analogous motor driven devices. The object of my invention as to provide a simple, 15 economical and effective electric motor attachment to the winding shaft of a prime motor, whereby the prime motor may be rewound automatically by closing and opening a switch for controlling the current to 20 the electric motor.

Another object of my invention is to provide in combination with the rewind mechanism, means whereby the prime motor can be wound either automatically or manually 25 without interfering with the attachment.

Another object of my invention is to provide the electric driven motor shaft with a spring opposed slidable worm adapted to operate a one-way gear wheel which is 30 in clutch connection with the prime motor shaft, whereby the prime motor shaft can be either revolved by the electric motor through the worm, or it can be operated in the same direction for rewinding by coupling a manual crank to the rewind shaft.

With the above and other minor objects in view, the invention consists in certain peculiarities of construction and combination of parts, as are hereinafter set forth 40 with reference to the accompanying drawings and subsequently claimed.

In the drawings:

Figure 1 represents a side elevation of a 45 rewind mechanism attachment embodying the features of my invention, certain of the parts being in section as indicated by line 1-1 of Figure 2.

Figure 2 is a plan view of the same showing the rewind mechanism permanently attached to the inner wall of a musical instrument or phonograph.

Figure 3 is a side elevation of the device, with parts removed and parts in section, as indicated by line 2-2 of Figure 4.

55 Figures 4 and 5 are detail cross sections of the same, the sections being indicated re-

spectively by lines 4-4 and 5-5 of Figure 1, and

Figure 6 is a fragmentary detail sectional view of a part of the shiftable electric contact make and break mechanism, the section being indicated by line 6-6 of Figure 5.

Referring by characters to the drawings, A represents an electric motor having a split shell B extending from its front portion and 65 encasing the electric motor shaft 1, which shaft is journaled in the outer end of the shell, and is provided with an intermediate portion 1' that is polygonal in shape, as best shown in Figures 4 and 5. This polygonal or keyed portion 1' of the shaft has mounted thereon a worm 2, which is adapted to rotate with the shaft, but also has longitudinal motion thereon. The inner end of the worm is formed with a collar 2' and the 70 outer end is engaged by one end of a coil spring 3, which coil spring surrounds the shaft and its opposite end is in abutting engagement with the inner wall of the shell B, it being understood, however, that the ends 80 of the spring directly press against washers 4', which are interposed between the shell and wall and the end of the worm.

The shell B is provided with a circular chamber B' having transverse bearing apertures through which the winding shaft C of the prime motor extends, it being understood that this motor is of the ordinary type and forms no part of my invention, and is therefore not shown. However, the prime 90 motor is of the spring type. The outer end of the prime motor shaft C is provided with the usual threaded coupling socket for engagement with the corresponding threaded end of a winding crank C', which winding 95 crank extends through an aperture in the wall of the musical instrument, as best shown in Figures 2 and 4. Secured to the end of the winding shaft C is a bushing 5, the ends of which are journaled in the shell apertures and serve to support and align the end of the shaft C. The bushing is formed with an annular shoulder constituting a ratchet wheel 5', against which one face of a worm wheel 6 is arranged to abut, the worm wheel being loosely mounted upon the bushing and held against end play by spring ring 7. The ratchet wheel 5' is of the one-way type, as best shown in Figure 3, and its notched teeth are engaged by pawls 8, which are pivoted 105 to the juxtaposed face of the worm wheel.

As best shown in Figures 1, 2 and 5, the

shell B and its circular portion B' carry an electrical circuit make and break mechanism, which is adapted to open and close the electric circuit controlling the motor A. 5 The make and break mechanism comprises a fixed contact finger 9 and an oscillatory contact finger 9', which finger is connected to a yoke 10 that carries adjustable contact points 11 11'. These contact points are 10 aligned in a path of travel of a tappet pin 12, which tappet pin is carried by a block 13 that is guided and arranged to slide in a longitudinally disposed aperture 14 formed 15 in one wall of the barrel portion B of the shell. The inner end of the block 13 is of the spanner type and is nested within the shell B, the spanner portion being grooved to engage the collar 2' of the wall 2. 20 Referring to Figures 1 and 3, when the parts are in the position assumed in these two figures, the prime motor spring is unwound and the tappet pin 12, controlled by the worm is engaging the contact point 11', whereby the yoke is rocked upon its pivot to 25 close the contact fingers 9 and 9'. In this position, the current is introduced into the motor A, and due to its rotation, it will cause the worm wheel to revolve in the direction of the arrow, whereby the winding 30 shaft 6 is revolved and the associated prime motor spring will be wound, due to the fact that the one-way clutch mechanism comprising the ratchet wheel 5' and pawls 8, will turn the shaft C. 35 This action of the shaft and worm wheel will continue until the tension upon the spring of the prime motor has reached a pre-determined degree. Owing to the spring tension thus exerted in a revised direction 40 from that taken by the worm wheel, the worm 12 will travel toward the outer end of the motor shaft slowly in opposition to the resistance of the coil spring 3, and when the spring tension upon the prime motor 45 shaft is equalized by the tension of the compressed coil spring 3, the worm will have moved longitudinally of its shaft to approximately its full travel, this movement being permitted and limited by the length of the 50 slot 14 of shell B. Hence, it will be seen that the block 13 and its tappet 12 will at

this time have engaged the contact point 11 of the switch mechanism, whereby the yoke 10 will be again rocked upon its pivot to separate the contact fingers and thus break 55 the current or motor circuit, whereby said motor will come to a stop, and the prime motor is thus rewound. This action is repeated automatically when the prime motor spring requires rewinding, and the action 60 is thereby intermittent.

In conditions where it is desired to tension the prime motor before it unwinds to a point where it will be rewound by the automatic mechanism, I provide 65 means for coupling an ordinary hand crank C', as shown in Figure 4, to the prime motor rewinding shaft C. Hence, it will be observed that this manually controlled crank can effectually rewind the prime motor, 70 without disturbing the automatic rewind gear mechanism, due to the pawl and ratchet connection between the shaft C and the worm wheel 6.

I claim:

In a rewinding device for a prime motor having a winding shaft, provided with a coupling and a manually operated crank engageable with the coupling; the combination of a bushing secured to the winding shaft, 80 a one-way ratchet wheel carried by the bushing, a worm wheel loosely mounted upon the bushing, pawls carried by the worm wheel engageable with the ratchet wheel, an electric motor having a keyed shaft extension, a worm mounted upon the shaft extension adapted to rotate with and to move longitudinally thereof a housing for the shaft extension provided with apertures constituting bearings for the bushing, a spring 90 interposed between one end of the worm and housing to oppose movement of said worm in one direction, a tappet carried by the worm and an electric circuit make and break contact mechanism controlled by the 95 tappet.

In testimony that I claim the foregoing I have hereunto set my hand at Milwaukee, in the county of Milwaukee and State of Wisconsin.

WILLIAM KABEL.
